United States Patent Office

Des. 224,777
Patented Sept. 19, 1972

224,777

BOTTLE OR SIMILAR ARTICLE

Floyd E. Pettengill, Lancaster, Ohio, assignor to Anchor Hocking Corporation, Lancaster, Ohio

Filed Oct. 29, 1970, Ser. No. 25,718

Term of patent 14 years

Int. Cl. D9—01

U.S. Cl. D9—119

FIG. 1 is a side elevational view of a bottle or similar article showing my new design; and

FIG. 2 is a top view thereof.

I claim:

The ornamental design for a bottle or similar article, substantially as shown.
